UNITED STATES PATENT OFFICE.

EGBERT H. GOLD, OF SHELBY, INDIANA.

AUTOMATIC DEVICE FOR LOW-PRESSURE HEATING.

SPECIFICATION forming part of Letters Patent No. 768,019, dated August 16, 1904.

Application filed January 11, 1904. Serial No. 188,624. (No model.)

To all whom it may concern:

Be it known that I, EGBERT H. GOLD, a citizen of the United States, residing at Shelby, in the county of Lake and State of Indiana, have invented certain new and useful Improvements in Automatic Devices for Low-Pressure Heating, of which the following is a specification.

My present invention relates more particularly to improvements in that class of apparatus which is typically illustrated and claimed in my copending application, Serial No. 185,122, in which the supply of steam to a radiating system is automatically controlled, primarily, by means of an expansion device which is preferably exposed to the external atmosphere.

The object of my present invention is to provide an effective device of this class which shall be compact, which may be entirely located outside of any heated space—as, for instance, beneath a car—and which may be readily constructed in double form, so as to provide for the heating of both sides of a car.

These and such other objects as may hereinafter appear are attained by the devices shown in the accompanying drawings, in which—

Figure 1 is a vertical section through a part of a preferred form of my invention. Fig. 2 is a transverse section on the line 2 2 of Fig. 1 looking in the direction indicated by the arrows. Fig. 3 is a transverse section on the line 3 3 of Fig. 2 looking in the direction indicated by the arrows. Fig. 4 is an elevation of my improved apparatus, showing a part of the floor of a car and of the radiating-pipes with which my apparatus is connected. Fig. 5 is a horizontal section through a modified form of my apparatus. Fig. 6 is a section on the line 6 6 of Fig. 5, and Fig. 7 is a view in elevation of such modified form shown in connection with a part of a car-floor and a part of the car-heating pipes.

Like letters and numerals of reference indicate the same parts in the several figures of the drawings.

A indicates the floor of the car, B the train-pipe, C the radiating-pipes, D' the steam-supply pipes through which steam is supplied to the radiating-pipes, E the hand-operated control-valves, and F' the return-pipes.

G is the main casing of my control apparatus. This casing comprises a tubular section 1, adapted to be attached at each end to the train-pipe, an inlet-chamber 2, communicating with the tubular section 1, a strainer 3, and a pair of valve-chambers 4 4^a, communicating, respectively, with the inlet-chamber 2 and provided with valve-seats 5 5^a, to which are fitted valves 6 6^a to control the communication between said valve-chambers and the inlet-chamber 2. The casing G is also provided with outlet-chambers 7 7^a, which are separated from each other, but which communicate with the valve-chambers 4 4^a, respectively, only through the pipes of the radiating system. 65 Communication between the chambers 7 7^a and 4 4^a, respectively, is closed by perforated plugs 8, through which reciprocate the stems 9 9^a of the valves 6 6^a. Each of said stems is provided with a polygonal collar 10, between which and the plugs 8 are loosely mounted packing-washers 11, which are adapted to fit against the under face of the plugs 8. Secured to the upper ends of the valve-stems 9 9^a are caps 12, provided on their under faces with annular seats 75 for receiving helical springs 13, which surround the valve-stems 9 9^a and which are seated at their lower ends upon the perforated plugs 8. The caps 12 are each provided with a headed stem 14. Pivotedly mounted within 80 the chambers 7 7^a are levers 15, which are preferably forked at their ends, one forked end engaging the headed stem 14 of a cap 12 and the other forked end being pivotally secured to a vertical stem 16. Communicating with 85 the outlet-chambers 7 7^a are diaphragm-chambers 17 17^a, within which are located expandible diaphragms 18 18^a of a familiar type, said diaphragms being so mounted that water and steam may flow around them and out through 90 perforations in the bottom of the casings 19, surrounding the diaphragm-chambers. The outlet-pipes F F' communicate, respectively, with the outlet-chambers 7 7^a.

The apparatus as so constructed is mounted as shown in Fig. 4—that is, below the floor of a car—so that any difficulty in fitting the apparatus to a car is simplified, because all of the working parts may be located outside of the car, and the car-floor need be perforated. 95 100

only for the passage of the discharge and supply pipes.

The operation of the apparatus as so constructed is as follows: The train-pipe B being filled with high-pressure steam in the usual manner, steam therefrom passes through the steam-chamber 2 and thence through the control-valves in the valve-chambers 4-4^a, whence it passes into the steam-supply pipes D D'. It will be understood that the radiating system leading from the valve-chamber 4 is entirely distinct and disconnected from the radiating system leading from the valve-chamber 4^a, one system being used in one side of the car and the other system upon the other side. The valve E being opened manually, steam is free to flow through the pipe D, the radiating-pipes C, and back through the discharge-pipes F into the chamber 7, thence to the chamber 17, and thence around the diaphragm 18 and to the atmosphere. It will be evident that as soon as the radiating and discharge pipes become filled with steam at such a high temperature that the steam or vapor reaching the valve-chamber 17 will sufficiently expand the diaphragm 18 the stem 16, being operated by the expansion of the diaphragm 18, will move the lever 15 upon its pivot, thereby causing the depression of the valve-stem 9 against the expansion of the spring 13 and closing the inlet-valve 6. Upon the lowering of the temperature in the radiating system, so that the diaphragm 18 at the extreme further end of the radiating system shall contract, the reverse operation takes place and the valve 6 opens, admitting fresh steam. The apparatus will soon balance itself, so that the amount of steam admitted at train-pipe pressure through the valve 6 will be just sufficient to keep the diaphragm 18 partially expanded, so as not to entirely shut off the steam-supply nor to admit the steam at full pressure. Any reduction in the external temperature will result in a further contraction of the diaphragm 18 and a correspondingly-increased supply of live steam through the valve 6.

With this explanation of the operation of the apparatus it will be seen that the efficiency of the apparatus is increased by conducting the water of condensation and the steam through the exposed pipes F to the discharge-chamber 7 before conducting it to the diaphragm-chamber 17, because the vapor which flows into the pipe F, having already lost much of its temperature by radiation from the radiating-pipes, will be still further and quickly cooled because of the exposed position of the pipe F, so that the diaphragm will remain contracted until the radiating-pipes C are filled with such a body of live steam that notwithstanding the reduction of its temperature, which takes place as it flows through the exposed pipe F, the steam will still be of a sufficiently high temperature

when it reaches the diaphragm 18 to cause the diaphragm to expand to such an extent as to allow just enough high-pressure steam to flow through the valve 6 to keep the radiating-pipes C filled with live and effective steam. At the same time I am enabled by this construction to keep the apparatus in a strong and compact form and in a comparatively small compass, so that the apparatus may be mounted close to the bottom of the car, where it will not be so readily damaged as if it were otherwise constructed and located.

By mounting my apparatus in duplicate, so as to provide for both sides of the car in one device, I not only attain the advantage of compactness, but obtain an additional element of safety for the following reason: Whenever either radiating system is shut off by closing the manually-operated supply-valve E, there is always a possibility of some water of condensation remaining in the pipes and slowly trickling into the outlet-pipe F, for because of the high pressure in the train-pipe some vapor may leak through the valve E and condense in the radiating-pipes, the water of condensation thereafter slowly trickling down into the pipe F. Because of the exposed position of the pipe F water of condensation would tend to freeze, and this continual operation of condensing, trickling, and freezing might under some conditions result in ultimately stopping the passage through the pipe F; but with my apparatus constructed as shown if either side of the heating apparatus is in operation there will be a continual flow of live steam therethrough, the hottest temperature of which will be within the steam-chamber 2, which flow of hot steam will heat the casing G and will also sufficiently warm the air within the chamber 7, and so within the pipe F, to prevent the freezing of water within the pipe F.

In Figs. 5, 6, and 7 I have shown my apparatus further modified by mounting the casing G horizontally instead of vertically, thereby enabling me not only to adapt it to other situations and to still further place my apparatus out of harm's way, but to attain further advantages in the operation of the apparatus. It will be noted that in this modified structure the casings 19^a, containing the diaphragm-chambers, are arranged horizontally, so that the water of condensation and return steam from the return-pipes F F' will not flow through the chambers 19^a and thence to the atmosphere, but will flow through outlet-ports 20 in the bottom of the chambers 7^b 7^c. By means of this construction the water of condensation never enters the diaphragm-chamber, the diaphragm is not affected by hot water, which, coming in contact therewith, would tend to partially expand the diaphragm, but the diaphragm remains contracted until the vapor flowing through the return-pipes

F is of such a temperature that entering the diaphragm-chambers and surrounding the diaphragms it will promptly expand the diaphragms, while, on the other hand, as soon as the vapor flowing through the pipe F cools the diaphragm may promptly contract. I thus obtain a more sensitive operation and prompt response of the control device than in the structures shown in the other figures. It will be noted that in this modified form I have shown springs 21 arranged in the diaphragm-chambers and expanding against plates 22, which are arranged on the faces of the diaphragms and surrounding the flanges secured to the lower ends of the stems 16 16", so as to insure the prompt opening of the valves 6 6" upon the contraction of the diaphragms, although it is entirely possible to dispense with all springs and rely upon steam-pressure to open the valves 6 6".

In the structure shown the diaphragms are provided with the usual adjusting-screws and lock-nuts 23 24.

I do not hereby claim any apparatus comprising a radiating system communicating with the atmosphere combined with a thermostatic motor exposed within said system and arranged to control the admission of a heating medium to its inlet end, as disclosed and claimed in my Patent No. 758,436, dated April 26, 1904.

I claim--

1. In a device of the class described, the combination with a radiating system located within a space to be heated, of means for controlling the supply of a heating medium to said radiating system, said means being located outside of the space to be heated by the radiating system and comprising a casing containing a chamber through which the heating medium is supplied to the radiating system, a control-valve mounted within said casing, so as to control the flow of the heating medium to the radiating system, a second chamber, an exposed return-pipe leading from the radiating system to said second chamber, mechanism mounted within said second chamber and arranged to operate said control-valve, and a thermostatic device exposed to the temperature of vapor flowing into said chamber through said return-pipe and arranged to actuate said valve-operating mechanism, substantially as described.

2. In a device of the class described, the combination with two independent radiating systems located within a space to be heated, of means for separately controlling the supply of a heating medium to said radiating systems, said means comprising a casing located outside of the space to be heated by the radiating systems, separate return-pipes located outside of the space to be heated and leading from said radiating systems, respectively, to separate chambers within said casing, thermostatic devices exposed, respectively, to the temperature of vapor flowing into said chambers through said return-pipes and arranged to actuate said valve-operating mechanism, substantially as described.

temperature of the vapor flowing through said return-pipes and mechanism operated by said thermostatic devices respectively, for controlling the supply of the heating medium to said respective radiating systems.

3. In a device of the class described, the combination with a radiating system, of a casing communicating with both ends of the radiating system and provided with mechanism for controlling the supply of a heating medium to said radiating system, a thermostatic device arranged to actuate said controlling mechanism and exposed to the action of the vapor returning to said casing from the radiating system, said casing being provided with an outlet interposed between the return-pipe from the radiating system and the thermostatic device, for the discharge of water of condensation.

4. In a device of the class described, the combination with a radiating system in open communication with the atmosphere, of a casing communicating with both ends of the radiating system and provided with mechanism for controlling the supply of a heating medium to said radiating system, a thermostatic device arranged to actuate said controlling mechanism and exposed to the action of the vapor returning to said casing from the radiating system, said casing being provided with an outlet interposed between the return-pipe from the radiating system and the thermostatic device, for the discharge of water of condensation.

5. In a device of the class described, the combination with two independent radiating systems located within a space to be heated and in open communication with the atmosphere, of means for separately controlling the supply of a heating medium to said radiating systems, said means comprising a casing located outside of the space to be heated by the radiating systems, separate return-pipes located outside of the space to be heated and leading from said radiating systems, respectively, to separate chambers within said casing, thermostatic devices exposed, respectively, to the temperature of the vapor flowing through said return-pipes and mechanism operated by said thermostatic devices, respectively, for controlling the supply of the heating medium to said respective radiating systems.

6. In a device of the class described, the combination with a radiating system, in open communication with the atmosphere, located within a space to be heated, of means for controlling the supply of a heating medium to said radiating system, said means being located outside of the space to be heated by the radiating system and comprising a casing containing a chamber through which the heating medium is supplied to the radiating system, a control-valve mounted within said casing, so as to control the flow of the heating medium

to the radiating system, a second chamber, an exposed return-pipe leading from the radiating system to said second chamber, mechanism mounted within said second chamber and 5 arranged to operate said control-valve, and a thermostatic device exposed to the temperature of vapor flowing into said chamber

through said return-pipe and arranged to actuate said valve-operating mechanism, substantially as described.
